Primary Examiner — Cynthia Ramirez(74) *Attorney, Agent, or Firm* — Buchanan Ingersoll & Rooney PC(57) **CLAIM**

The ornamental design for a waste container, as shown and described.

DESCRIPTION

FIG. 1 is a front perspective view of a waste container, in a closed position, according to my new design.

FIG. 2 is a front elevation view thereof.

FIG. 3 is a left side elevational view thereof, the other side being a mirror image.

FIG. 4 is a top plan view thereof.

FIG. 5 is a bottom plan view thereof.

FIG. 6 is a front perspective view thereof, in an open position.

FIG. 7 is a front elevational view thereof.

FIG. 8 is a left side elevational view thereof, the other side being a mirror image.

FIG. 9 is a top plan view thereof; and,

FIG. 10 is a bottom plan view thereof.

The broken line showing of the wall structure on which the waste container is mounted and the portion of the waste container recessed with the wall structure is for environmental illustration only and forms no part of the claimed design.
